1,3-BENZOXAZINE - 2:4 - DIONE AND PHARMACOLOGICALLY ACCEPTABLE ALKALI METAL SALTS THEREOF AS ANALGESICS

Leslie Frederick Wiggins, Wargrave, England, assignor to Aspro-Nicholas Limited, Slough, England, a British company

No Drawing. Filed July 21, 1961, Ser. No. 125,647

Int. Cl. A61k 27/00

U.S. Cl. 424—248

7 Claims

This invention relates to new pharmaceutical preparations and their use in medicine.

It has been found that the compound 1:3-benzoxazine-2:4-dione exhibits hypnotic, tranquillising and analgesic activity and is non-gastric irritant, and clinical trials have shown that the compound may be used for the relief of pain in human patients suffering from headache or rheumatic pain. The compound has been found to be a quick-acting analgesic when given by the oral route.

The 1:3-benzoxazine-2:4-dione forms alkali metal salts, such as the sodium salt, which may be employed in place of the dione itself.

The toxicity of the compound is such that doses of up to 1000 milligrams may be administered orally say three times a day, whereas its activity is such that doses as low as 10 milligrams each may be employed.

The present invention provides a method of treating a person suffering from various types of pain which includes the step of administering to that person at least one dose of from 10 to 1000 milligrams of at least one analgesic compound selected from the class consisting of 1:3-benzoxazine-2:4-dione and pharmacologically acceptable alkali metal salts thereof.

In accordance with the invention, there is also provided a pharmaceutical preparation in dosage unit form comprising 1:3-benzoxazine-2:4-dione or a pharmacologically acceptable alkali metal salt thereof as the active component, together with one or more solid or liquid pharmaceutical diluents or carriers.

The dosage unit may contain from 10 to 500, or even 1000, milligrams of the active component. Preferably, the content thereof is from 20 to 200 milligrams or, more advantageously, between 40 and 120 milligrams. In practice, the dosage may well be 50 or 100 milligrams and it is therefore preferred to provide tablets or other dosage units each containing 50 or 100 milligrams of the 1:3-benzoxazine-2:4-dione.

The dosage unit of the pharmaceutical preparations of the present invention may exist in any of the customary pharmaceutical forms, such as for example tablets, capsules, cachets, packaged powders, pills, ampouled solutions for parenteral administration, suppositories for rectal administration and suspensions for oral administration, although a form adapted for oral administration, especially tablets, is preferred.

The percentage of active component in the pharmaceutical preparation may be varied, providing that the preparation, irrespective of the particular form in which the dosage unit may exist, contains sufficient of the active component to have the required pharmacological effect. In general, the preparation should normally contain at least 0.25% by weight of the active component when required for oral administration and at least 0.1% by weight of the active component when required for administration by injection. If desired, several dosage unit forms may be administered at about the same time.

Some examples of the pharmaceutical diluents or carriers which may be employed in the pharmaceutical preparations of the invention are sugars such as lactose and sucrose; maize starch; talc; magnesium stearate; calcium phosphate; liquid paraffin; oil of theobroma; citric acid;

2

syrup B.P.; methyl cellulose; methyl and propyl hydroxybenzoate; and polyoxyethylene sorbitan monolaurate.

If desired, the pharmaceutical preparations may contain, in addition to the active component 1:3-benzoxazine-2:4-dione, one or more other pharmacologically active substances, for example acetylsalicylic acid, phenacetin, caffeine, codeine, salicylamide, phenazone, iso-propyl phenazone, paracetamol(N-acetyl-p-aminophenol) or amidopyrine. They may, for example, contain phenacetin and also caffeine and/or codeine.

The alkali metal salts of 1:3-benzoxazine-2:4-dione which may be employed in accordance with the present invention are novel compounds. By way of example, the sodium salt is a white crystalline salt which does not melt up to 310° C. and which is soluble in water to at least 10%, a solution of a concentration of 10% exhibiting a pH of 8.3. This salt may be made by adding to a boiling solution of 25 g. of 4-hydroxycoumarin in 300 ml. of dry ethanol a solution obtained by dissolving 7.0 g. of sodium metal in 100 ml. absolute ethanol. A precipitate forms and on cooling is filtered off and washed with alcohol. After drying, its weight is 23.5 g. Sodium found 12.4%; calculated 12.5%.

To illustrate the invention, the following specific examples of pharmaceutical preparations in accordance with the invention will now be given.

Example 1

Tablets were prepared from the following:

	G.
1:3-benzoxazine-2:4-dione	400
Lactose	80
Maize starch, dried	119
Magnesium stearate	1

The 1:3-benzoxazine-2:4-dione, lactose and 89 g. of starch were well mixed and then mixed with a starch paste prepared from the remaining 30 g. of starch and about nine times its weight of hot water. The resulting mass was granulated through a No. 10 mesh B.S.S. sieve and dried at 40 to 50° C. The dried granules were passed through a No. 12 mesh B.S.S. sieve and then well mixed with the magnesium stearate. The resulting granules were then compressed so that each tablet weighed 600 mg. and contained 400 mg. of 1:3-benzoxazine-2:4-dione. The tablet may be scored so that half or quarter of this dosage may be taken.

Example 2

Dried granules obtained as in Example 1 were passed through a No. 16 mesh B.S.S. sieve and then well mixed with the magnesium stearate. The resulting granules were then compressed so that each tablet weighed 150 mg. and contained 100 mg. 1:3-benzoxazine-2:4-dione. The tablet may be scored so that half or quarter of this dosage may be taken.

Example 3

100 g. of 1:3-benzoxazine-2:4-dione were mixed with 1 g. of calcium phosphate and the resulting powdered mixture was filled into hard gelatin capsules such that each contained 100 mg. of the active component.

Example 4

100 g. of 1:3-benzoxazine-2:4-dione were milled with 25 g. of liquid paraffin and 125 mg. of the resulting suspension were filled into each soft gelatin capsule which then contained 100 mg. of the active component.

Example 5

100 g. of 1:3-benzoxazine-2:4-dione were mixed with 1 g. of calcium phosphate and the resulting powdered mix-

ture was filled into cachets such that each contained 400 mg. of the active component.

Example 6

100 g. of 1:3-benzoxazine-2:4-dione were well mixed with 100 g. of lactose, the resulting powder being packaged so that each individual packaged powder contained 400 mg. of 1:3-benzoxazine-2:4-dione.

Example 7

A suspension containing 100 mg. of 1:3-benzoxazine-2:4-dione per 4 ml. teaspoonful was prepared from the following:

1:3-benzoxazine-2:4-dione	g.	2.5
Methyl cellulose, powdered, 450 ¹	g.	1.0
Syrup B.P.	ml.	30.0
Methyl hydroxybenzoate	g.	0.1
Propyl hydroxybenzoate	g.	0.02
Orange oil	ml.	0.5
Citric acid	g.	0.1
Polyoxyethylene sorbitan monolaurate	g.	3.0
Glycerin	ml.	5
Distilled water to	ml.	100

¹ This figure represents the viscosity in centipoises of a 2% solution in water at 20° C. as determined in an Ostwald viscometer or a falling sphere viscometer (B.S.S.188:1937).

The methyl and propyl hydroxybenzoates were dissolved by boiling in 35 ml. of distilled water and the methyl cellulose was dispersed by stirring in the resulting solution when cooled. The citric acid was dissolved in the resulting mucilage, to which the syrup was then added and mixed therein. The resulting mixture was then triturated with the 1:3-benzoxazine-2:4-dione to form a smooth suspension.

The orange oil was mixed with the polyoxyethylene sorbitan monolaurate to form a mixture to which the glycerin was added. The resulting mixture was then added to the abovementioned suspension. Distilled water was thereafter added to volume and the mixture stirred to form a homogeneous suspension.

Example 8

Suppositories containing 200 mg. of 1:3-benzoxazine-2:4-dione in each were prepared as follows:

20 g. of 1:3-benzoxazine-2:4-dione were finely powdered and triturated with 80 g. of melted oil of theobroma to form an even suspension. The molten suspension at approximately 45° C. was poured into lubricated suppository moulds of nominal 1 g. capacity to produce suppositories each containing 200 mg. of 1:3-benzoxazine-2:4-dione.

Example 9

Tablets each containing 100 mg. of 1:3-benzoxazine-2:4-dione and 324 mg. of aspirin were prepared from the following:

A:		G.
1:3-benzoxazine-2:4-dione	100	
Lactose	20	
Maize starch, dried	30	
B:		
Aspirin	324	
Maize starch, dried	64.8	
Talc, purified	21.2	

A. The 1:3-benzoxazine-2:4-dione, lactose and 22.5 g. of starch were well mixed and the resulting mixture was mixed with a starch paste prepared from the remaining 7.5 g. of starch and water. The resulting mass was granulated through a No. 10 mesh B.S.S. sieve and dried at 40 to 50° C. The dried granules were then passed through a No. 12 mesh B.S.S. sieve.

B. The aspirin and starch were well mixed and tablets were prepared from the resulting mixture by preliminary compression or "slugging." The "slugs" so formed were

broken down and passed through a No. 10 mesh B.S.S. sieve.

The granules A and slugs B were well mixed and the talc, passed through a No. 60 mesh B.S.S. sieve, was added to the mixed granules. After again mixing, the granules were compressed into tablets each weighing 560 mg. and containing 100 mg. of 1:3-benzoxazine-2:4-dione and 324 mg. of aspirin.

Example 10

Tablets were prepared from the following:

1:3-benzoxazine-2:4-dione	50	G.
Phenacetin	150	
Caffeine	30	
Lactose	88	
Maize starch (dried)	80	
Magnesium stearate	2	
	400	

The 1:3-benzoxazine-2:4-dione, phenacetin, caffeine, lactose and 60 g. of the maize starch were well mixed and then massed together with starch paste prepared from the remaining 20 g. of maize starch and water. The resulting mixture was granulated through a No. 10 mesh B.S.S. sieve and dried at 40° to 50° C. The dried granules were passed through a No. 12 mesh B.S.S. sieve and well mixed with the magnesium stearate which had previously been passed through a No. 60 mesh B.S.S. sieve. The resulting granules were then compressed so that each tablet weighed 400 mg. and contained 50 mg. 1:3-benzoxazine-2:4-dione, 150 mg. phenacetin and 30 mg. caffeine.

Example 11

Tablets were prepared from the following:

1:3-benzoxazine-2:4-dione	50	G.
Lactose	10	
Maize starch (dried)	14.9	
Magnesium stearate	0.1	

The 1:3-benzoxazine-2:4-dione, lactose and 11.0 g. of the starch were well mixed and then mixed with a starch paste prepared from the remaining 3.9 g. of starch and water. The resulting mass was granulated through a No. 10 mesh B.S.S. sieve and dried at 40° C. to 50° C. The dried granules were passed through a No. 16 mesh B.S.S. sieve and were then well mixed with the magnesium stearate. The resulting granules were then compressed so that each tablet weighed 75 mg. and contained 50 mg. of 1:3-benzoxazine-2:4-dione. The tablets may be scored so that half or a quarter of this dosage may be taken.

I claim:

1. A method of obtaining an analgesic effect which comprises administering an analgesically effective non-toxic quantity of a compound selected from the group consisting of 1:3-benzoxazine-2:4-dione and pharmacologically acceptable alkali metal salts thereof.

2. A method in accordance with claim 1 in which the compound is administered in a dose which comprises from 10 to 1000 milligrams of the compound.

3. A method in accordance with claim 1 in which the compound is administered orally.

4. A pharmaceutical preparation in dosage unit form adapted for administration to obtain an analgesic effect, comprising, per dosage unit, an analgesically-effective nontoxic amount within the range from about 10 to about 1000 milligrams of at least one compound selected from the group consisting of 1:3-benzoxazine-2:4-dione and pharmacologically acceptable alkali metal salts thereof, and a pharmaceutical diluent.

5. A pharmaceutical preparation in accordance with claim 4 in a form adapted for oral administration.
6. A pharmaceutical preparation in accordance with claim 5 in the form of a tablet.
7. A pharmaceutical preparation in accordance with claim 4 comprising phenacetin and at least one compound selected from the group consisting of caffeine and codeine.
